UNITED STATES PATENT OFFICE.

ROBERT F. CARPENTER, OF CLEVELAND HEIGHTS, OHIO.

DESIGN FOR A METAL STALL.

51,672.

Specification for Design. Patented Jan. 8, 1918.

Application filed March 11, 1916. Serial No. 83,661. Term of patent 7 years.

To all whom it may concern:

Be it known that I, ROBERT F. CARPENTER, a citizen of the United States, residing at 3031 Lincoln Boulevard, Cleveland Heights village, Cuyahoga county, Ohio, have invented a new, original, and ornamental Design for a Metal Stall, of which the following is a specification, reference being had to the accompanying drawing, forming part thereof.

Figure 1 is a perspective view of a metal stall showing my new design. Fig. 2 is a vertical section thereof.

I claim:

The ornamental design for a metal stall, as shown.

ROBERT F. CARPENTER.

Witnesses:

W. M. M. MONROE,
W. M. J. KLOTZBOCH.
